UNITED STATES PATENT OFFICE

96,832

DESIGN FOR A PORTABLE COMBINED PHONOGRAPH AND RADIO

Arthur Hill, New York, N. Y.

Application April 4, 1935, Serial No. 56,216

Term of patent 7 years

To all whom it may concern:

Be it known that I, Arthur Hill, a citizen of the United States and a resident of the Borough of Manhattan, county, city, and State of New York, have invented a new, original, and ornamental Design for a Portable Combined Phonograph and Radio, of which the following is a specification, reference being had to the accompanying drawing, forming part thereof, wherein,

Figure 1 is a perspective view of the invention in open condition, and

Fig. 2 is a perspective view of the invention in closed condition.

The characteristic features of my design reside in that the portable cabinet which houses the

combined phonograph and radio has a normally hidden end panel with a circular grille therein and a horizontal top panel with a grille therein adjacent the normally hidden end panel, said grilles being rendered visible when the device is in the open position shown in Fig. 1, and that when closed the device has the appearance of a travelling case.

I claim:

The ornamental design for a portable combined phonograph and radio as shown and described.

In witness whereof, I have hereunto set my name.

ARTHUR HILL.
